UNITED STATES PATENT OFFICE

SAMUEL B. McHENRY, OF CHICAGO, ILLINOIS.

DUST-MOP.

1,080,711.

Specification of Letters Pat...

Patented Dec. 9, 1913.

Application filed June 22, 1912. Serial No. 705,196.

To all whom it may concern:

Be it known that I, SAMUEL B. McHENRY, a citizen of the United States, and a resident of the city of Chicago, county of Cook, and

State of Illinois, have invented certain new and useful Improvements in Dust-Mops, of which the following is a specification.

This invention relates to dust mops and is designed to construct a device of this nature wherein the body or mop block will always rest in a constant plane parallel to the surface over which it is operated irrespective of the position of the handle.

Another object of the present invention is the provision of a mop wherein the mop block is supported above the surface over which it is operated by the mop strands irrespective of the relative position of said strands to the mop block.

With the above and other objects in view this invention consists in the construction, combination, and arrangement of parts all as hereinafter more fully described, claimed and illustrated in the accompanying drawing wherein:

Figure 1 is a top plan view of a dust mop forming the subject matter of the present invention, Fig. 2 is a transverse section illustrating in detail the coöperation of the handle with the block and the locking means for the mop strands, a portion of said strands being eliminated for the purpose of illustration.

Referring more particularly to the drawing, 10 indicates a circular disk which constitutes the mop block, said disk being provided with a central, concentric, conical depression 11 therein. A flexible strap 12 is arranged diametrically across the depression 11 and is retained in this position by means of the screws 13. A handle 14 is pivotally mounted on this strap 12 adjacent to the lower terminal thereof, the pivotal connection between said handle and said strap being such that a portion of the handle projects into the depression 11. It will clearly be seen that as the mop is pushed or drawn by the handle over a surface, the handle 14 will assume various angles to the plane of the mop block 10 in such a manner that said mop block will be retained in a normally constant plane. In order that the strap 12 may not be subjected to any unusual strains it will be understood that the lower terminal

of the mop handle 14 which projects into the depression 11 will bear against the walls of the depression 11 irrespective of the positions of the handle thus causing the strain to be applied upon the mop block direct and not upon the strap 12.

The mop strands which are used in the preferred form of construction are woolen yarn strands which are rebent forming a loop, said loop being retained in a groove 15 formed in the under side and adjacent to the periphery of the mop block 10. This groove 15 is formed in the under side of the block 10 adjacent to the periphery thereof, said groove extending inwardly into said block at an acute angle to the horizontal plane, the outer side of said groove forming a lip 16 which constitutes the edge of the block and is curved as illustrated, the opposite side 17 thereof being curved to conform with the curve of the lip 16. The body of the block 18 surrounded by the lip 16 is at a slightly lower elevation than said lip, as is illustrated in Fig. 2, and aids in retaining the welt or bead in the woolen yarn strands 19 which support the block above the surface operated upon, as will hereinafter be more fully described. As is heretofore stated, the woolen yarn strands 19 are rebent forming a loop 20 which is forced into the groove 15. A continuous wire 21 is attached by one end to the inner surface of the groove, as at 22, then is wound about within the groove three times, said wire extending through the loop 20 of the strand and has its free end attached to the block, as at 23. From this construction it will clearly be understood that the oblique and angular arrangement of the inner portion 18 of the block and the formation of the lip 16 causes the strands 19 to be curved downwardly, as illustrated in Fig. 2, forming a welt or ridge which contacts with the surface operated upon and supports the block 10 above said surface. This ridge or welt is retained irrespective of the position of the strands by reason of the formation of the inner side 17 of the groove 15.

While I have illustrated and described the preferred form of construction for carrying my invention into effect, this is capable of variation and modification without departing from the spirit of the invention. I, therefore do not wish to be limited to the precise details of construction set forth, but

desire to avail myself of such variations and modifications as come within the scope of the appended claim.

Having described my invention what I claim as new and desire to secure by Letters Patent is:

In combination, a mop head comprising a disk having an annular groove opening upon the bottom face of the head and extending therein from its lower peripheral edge obliquely toward the center of the upper face, the side of said groove nearer the

periphery of said disk being convex and the other side of said groove being concave; and mop material secured in said groove, substantially as described.

In testimony whereof I have signed my name to this specification in the presence of two subscribing witnesses.

SAMUEL B. McHENRY.
